UNITED STATES PATENT OFFICE

2,128,535

LATCH OPERATING MEANS

George D. Lindstrom and Edwin North, Rockford,
Ill., assignors to National Lock Co., Rockford,
Ill., a corporation of Illinois

Original application February 20, 1935, Serial
No. 7,380. Divided and this application Sep-
tember 3, 1936, Serial No. 99,201

11 Claims. (Cl. 292—166)

This invention is a division of applicants' co-pending application, Serial No. 7,380, filed February 20, 1935, on a Door latch mechanism.

This invention relates to certain novel improvements in latch operating means, and has for its principal object the provision of an improved construction of this character which will be highly efficient in use and economical in manufacture.

A further object of the invention is to provide a latch operating mechanism which is operated by a pull or push movement on a handle or lever operatively associated with a latch structure.

A still further object of the invention is the provision of a latch operating mechanism for a door in which the handle operated latch operating mechanism is completely concealed from view, thereby exposing only the latch bolt and its keeper plate.

Other objects will appear hereinafter.

20 The invention consists in the novel combination and arrangement of parts to be hereinafter described and claimed.

The invention will be best understood by reference to the accompanying drawing, showing the preferred form of construction, and in which:

Fig. 1 is a side elevational view, partly in section, showing the new door latch operating means in normal position;

Fig. 2 is a front elevational view of the same; 30 Fig. 3 is a fragmentary side elevational view showing the new door latch operating handle in one of its two latch operating positions; and

Fig. 4 is a fragmentary side elevational view showing the new latch operating means in another of its latch operating positions.

A bracket structure 50 is provided to secure the new latch operating means to the closure member with which it is to be associated; the connection being accomplished through the medium of screw elements which are disposed through the openings 51. This bracket structure provides spaced ears 52, and pivotally supported by these ears 52 between the latter by means of a pintle 53 is a handle 54. This handle 54 provides oppositely disposed rollers or bearing elements 55 and 56 carried by the handle through the medium of pintles 57 and 58.

These roller elements 55 and 56 are adapted to have alternate engagement with a plate 58 pivotally supported from a pintle 59 carried by the ears 52. This plate 58 is operated upon by a spring element 60 supported by the pintle 59, and is urged by this spring to bear against the roller elements to retain the handle element 54 in a posi-

tion substantially midway between its two extreme points of movement.

The plate 58 is adapted to be brought into engagement with the head 61 of a pin 50' by action of the bearing rollers 55 or 56 upon the plate 58. 5 This pin 50' is slidably mounted in a bearing sleeve 61' formed in the bracket structure 50 and is connected by a threaded bearing portion 69 thereof to a button element 47. It is through the 10 slidable movement of the pin 50' and its associated parts that latch operating movement is imparted by the handle mechanism.

The latch operating mechanism shown in Fig. 1 may be positioned as shown in Fig. 3 by pressing the handle 54 inwardly (clockwise Fig. 1), whereupon the roller 55 will act upon the pivoted plate 58 to urge the latter against the head 61 of the pin 50', thereby imparting latch operating movement by means of the button 47. By pulling the handle 54 outwardly (counterclockwise, Fig. 1), the roller 20 56 will act upon the pivoted plate 58 to urge the latter against the head 61, as shown in Fig. 4; the latch operating movement of the pin 50' being the same in both instances.

While we have illustrated and described the preferred form of construction for carrying our invention into effect, this is capable of variation and modification without departing from the spirit of the invention. We, therefore, do not wish to be limited to the precise details of construction set forth, but desire to avail ourselves of such variations and modifications as come within the scope of the appended claims.

Having thus described our invention, what we claim as new and desire to protect by Letters 35 Patent is:

1. A latch-operating device including a support, a handle pivotally mounted on said support for unlatching operation in opposite directions, an intermediate latch-operating lever pivotally 40 mounted on said support in a position to be engaged and pivoted in a particular direction by pivotal movement of said handle in either of said opposite directions, together with a reciprocably movable latch-operating element positioned for 45 operative engagement and movement in said particular direction by said intermediate operating lever.

2. A latch-operating mechanism comprising a latch-operating member, a supporting member 50 adapted to be secured to a closure member such as a door or the like, a handle pivotally mounted upon the said supporting member and movable into latch-releasing position in either of two opposite directions, a member pivotally mounted 55

- upon the said supporting member and having a portion engageable with the said latch-operating member, a pair of rollers carried by the said handle and arranged on opposite sides of the pivotal mounting of the latter and engageable selectively with said fourth-named member so as to move the said portion of the latter into engagement with said latch-operating member, and means normally urging the said fourth-named member into engagement with the said rollers so as to move the said handle into its normal or ineffective position substantially midway between the limits of its movement.
3. A latch-operating mechanism for a latching device which includes a latch operating member, said latch-operating mechanism comprising a support adapted to be secured to a closure member such as a door or the like, a handle pivotally mounted upon the said support and movable into latch-releasing position in either of two opposite directions, a member pivotally mounted upon the said support and having a portion engageable with the said latch-operating member so as to move the latter into latch-releasing position, a pair of bearing elements carried by the said handle and arranged on opposite sides of the said pivotal mounting of said handle and engageable selectively with the said third-named member so as to move the said portion of the latter into engagement with said latch-operating member, and means normally urging the said third-named member into engagement with said bearing elements so as to move the said handle into its normal position substantially midway between the limits of its movement.
4. A latch-operating mechanism comprising a latch-operating member, a supporting member adapted to be secured to a closure member such as a door or the like, a handle pivotally mounted upon the said supporting member and movable into latch-releasing position in either of two opposite directions, a member pivotally mounted upon the said supporting member and having a portion engageable with the said latch-operating member so as to move the latter into latch-releasing position, a pair of rollers carried by the said handle and arranged on opposite sides of the pivotal mounting of the latter, and engageable selectively with said fourth-named member so as to move the said portion of the latter into engagement with said latch-operating member, and a spring normally urging said fourth-named member into engagement with the said rollers so as to move the said handle into its normal or ineffective position substantially midway between the limits of its movement.
5. A latch-operating mechanism for a latching device which includes a latch-operating member, said latch-operating mechanism comprising a support adapted to be secured to a closure member such as a door or the like, a handle pivotally mounted upon the said support and movable into latch-releasing position in either of two opposite directions, a member pivotally mounted upon the said support and having a portion engageable with the said latch-operating member so as to move the latter into latch-releasing position, a pair of bearing elements carried by the said handle and arranged on opposite sides of the said pivotal mounting of the latter and engageable selectively with the said third-named member so as to move the said portion of the latter into engagement with said latch-operating member, and a spring normally urging said third-named member into engagement with said bearing elements so as to move the said handle into its normal position substantially midway between the limits of its movement.

ment with the said bearing elements so as to move the said handle into its normal position substantially midway between the limits of its movement.

6. Latch-operating mechanism including a mounting for attachment to a door, a handle pivoted at one end on said mounting and being movable in opposite directions to operate a latch, a latch-operating member supported by said mounting, an intermediate operating lever pivoted at one of its ends on said mounting member and having an opposite end operatively engaging said latch-operating member and being disposed for engagement by portions of said handle when the latter is moved in either of its latch-operating directions.

7. Latch-operating mechanism including a mounting for attachment to a door, a handle pivoted at one end on said mounting and being movable in opposite directions to operate a latch, a latch-operating member supported by said mounting, an intermediate operating lever pivoted at one of its ends on said mounting member and having an opposite end operatively engaging said latch-operating member and being disposed for engagement by portions of said handle when the latter is moved in either of its latch-operating directions, together with spring means for said intermediate lever and operable to urge the same against said handle and maintain the latter in a position substantially intermediate its opposite latch-operating positions.

8. Latch-operating means including a substantially elongated support adapted for attachment to a closure, a latch-operating member mounted for reciprocable movement near an end of said support and laterally of the same, an intermediate operating lever pivotally mounted at an opposite end of said support and being engageable with said latch-operating member to move the latter in a direction outwardly of the support, a handle mounted at an end on said support at a point between said operating member and the pivoted end of said intermediate lever and movable pivotably in opposite directions against said intermediate lever to move said latch-operating member in the manner aforesaid.

9. Latch-operating means including a substantially elongated support adapted for attachment to a closure, a latch-operating member mounted for reciprocable movement near an end of said support and laterally of the same, an intermediate operating lever pivotally mounted at an opposite end of said support and being engageable with said latch-operating member to move the latter in a direction outwardly of the support, a handle mounted at an end on said support at a point between said operating member and the pivoted end of said intermediate lever and movable pivotably in opposite directions against said intermediate lever to move said latch-operating member in the manner aforesaid, and spring means normally urging said intermediate lever back against said end of the handle member to maintain the latter in a position substantially intermediate its two latch-operating positions.

10. Latch-operating means including a support for attachment to a closure or the like, an elongated latch-operating lever pivotally mounted near one of its ends on said support, a handle member pivotally mounted on said support with its pivotal axis extended collaterally with the pivotal axis of said lever and at a position at one side of said lever between the ends thereof in such manner that pivotal movement of said

handle in opposite directions will effect bearing engagement of parts of the handle, on substantially opposite sides of its own pivotal axis, against said lever to pivot the latter in a particular direction, latch mechanism on said closure and including a movable latch-operating element arranged with respect to said support so as to position said element in the path of movement of said lever in said particular direction for operative engagement and actuation by the latter.

11. Latch-operating means for use with closures equipped with latch mechanism of the type having a reciprocable actuating element, said 15 operating means comprising: a support adapted for mounting on said closure adjacent said actuating element; an intermediate operating lever pivotally mounted on said support for movement

in the direction of reciprocation of said actuating element, said lever being positioned so as to bear against said actuating element at a point remote from the pivotal axis of the lever; and a handle structure pivotally mounted on said support with its pivotal axis extended collaterally to that of said lever and so positioned and arranged that pivotal movement of said handle structure in opposite directions will cause parts on substantially opposite sides of the pivotal axis of said 10 handle structure to bear against portions of said lever located in the region at one side of the pivotal axis thereof toward said actuating element, whereby the latter may be moved in one particular direction by pivotal movement of the 15 handle in either direction.

GEORGE D. LINDESTRÖM.

EDWIN NORTH.
